RUDOLF E. HELLMUND, OF SWISSVALE, PENNSYLVANIA, ASSIGNOR TO WESTINGHOUSE ELECTRIC & MANUFACTURING COMPANY, A CORPORATION OF PENNSYLVANIA.

MEANS FOR AND METHOD OF ELIMINATING HARMONIC DISTURBANCES.

Application filed December 14, 1918. Serial No. 268,748.

To all whom it may concern:

Be it known that I, RUDOLF E. HELLMUND, a citizen of the German Empire, and a resident of Swissvale, in the county of Allegheny and State of Pennsylvania, have invented a new and useful Improvement in Means for and Methods of Eliminating Harmonic Disturbances, of which the following is a specification.

10 My invention relates to means for absorbing undesirable high-frequency currents which, while they may be necessary in the operation of certain electrical devices, are productive of unsatisfactory results when 15 allowed to flow in other portions of electrical circuits.

In many cases, it is necessary for satisfactory operation, that the load or translating device be supplied with currents of 20 the fundamental frequency only, but it frequently happens that undesirable harmonic currents may be introduced into the circuit by the source, by some other load, or by the condenser action of the line or condensive 25 apparatus operating thereupon under these circumstances, the undesirable harmonic currents should be prevented from flowing to the load.

Again, the load itself may cause the undesirable currents, and it then becomes necessary to keep such currents out of the line.

A specific application of my invention is the use of undesirable harmonic-current-absorption means in the circuits of alternating-current rectifiers. It is well known that, while alternating-current rectifiers require, for their satisfactory operation, currents of high frequency, it is desirable, if possible, to eliminate such high-frequency currents from 40 the remainder of the electrical circuit.

I propose, therefore, to associate with rectifier circuits, means which will eliminate the high-frequency currents from the load circuits fed by such rectifiers but, at the same time, propose to so connect the absorption means that the rectifier itself will derive the necessary supply of such currents for satisfactory operation.

For a better understanding of my invention, reference may be had to the accompanying drawings in which:

Figure 1 represents, diagrammatically, a load which causes currents having undesirable high frequencies, and the means for

eliminating such high-frequency currents; 55 Fig. 2 illustrates, diagrammatically, a system in which the undesirable currents are supplied to the line by the source or other instrumentalities exterior to the load itself; Figs. 3, 4 and 5 are diagrammatic views illustrating modifications of the systems shown in Figs. 1 and 2 and are especially related to the application of such systems to rectifier practices.

Referring more particularly to Fig. 1, a load requiring high harmonic currents is shown at 1 and is supplied with energy from any suitable source (not shown) by leads 2 and 3. Inserted in the leads 2 and 3 are inductive devices 4 and 5, for purposes hereinafter to be described.

Connected in parallel with the load 1 and between that load and the inductive devices 4 and 5, is a dynamo-electric machine 6 of the induction type having a primary member 7 and a squirrel-cage-wound secondary member 8. It will be noted that the primary member 7 is connected directly in parallel with the load 1 and that, therefore, it constitutes a shunt path for such currents as it 80 may be desired to pass therethrough.

In Fig. 2, the load 1 will operate satisfactorily with currents of the fundamental frequency only. As shown, however, the line 2-3 carries currents of undesirable frequency in addition to the device-operating currents. It is to be understood that such harmonic currents may come direct from the source, or it may be due to some other load on the same circuit, such as may be caused by the condenser action of the line, that is to say, it may be due to any instrumentality exterior to the load itself.

In this system, the eradicating means are connected between the source and the inductances 4 and 5 instead of between the load 1 and the inductances 4 and 5, as in Fig. 1.

In Fig. 3, a vapor rectifier 9 is shown as supplied with energy from a transformer 10 having a primary member 11 and a secondary member 12.

The rectifier 9 supplies direct current to the load 1, which is here shown as connected in a well known manner.

In this figure, the primary member 7 of 105 the induction machine 6 is shown as connected in parallel relationship with the transformer secondary 12. The rotor 8 of

the induction machine 6 is further provided with a direct-current winding 13 which is connected in parallel relationship to the inductive load and is, therefore, supplied 5 with direct current in the manner indicated.

An adjustable resistor 14 is connected in series relationship with the direct-current exciting winding 13, both being connected across the direct current terminals, and the 10 effective resistance of the exciting circuit is adapted to be varied by a segmental contact member 15 which is, in turn, rotated by an auxiliary dynamo-electric machine 16 comprising an armature 17 and a field winding 18, the armature 17 serving to rotatively actuate the contact segment 15 through a shaft 19. The field winding 18 is split and is supplied with energy in such a manner that the armature 17 may be made to rotatively move in either direction, in accordance with the movement of an auxiliary motor relay 20 comprising an armature 21 and a field winding 22. A contact making member 23 is attached to the armature 21, and 25 by its movement closes the circuit between contact terminals 24 and 25 or between contact terminals 26 and 27.

The entire apparatus just described comprises a power-factor relay which operates 30 to so vary the resistance of the resistor 14 that the excitation of the winding 13 is adjusted automatically to best suit the conditions obtaining in the induction machine 6, as, for instance, so that its line frequency 35 magnetizing current is zero or so that it furnishes wattless current to the transformer.

A series excited commutator machine 28, having an armature 29, series field winding 29^a and a neutralizing field winding 29^b, all connected as shown, is employed to further improve the absorption of undesirable harmonic currents by promoting the flow of such currents through the shunt circuit 45 rather than through the load.

For purposes of adjustment, impedances 30, 30^a, and 30^b are associated with the power-factor relay 20.

In Fig. 4, another modification of the system above described is shown. The inductance 5 is inserted in the primary side of the transformer, and across this inductance is connected the field winding 29^a of the commutator machine 28. For purposes of 55 convenience, I have not shown the power-factor relay as operatively connected in this figure, but it is to be understood that the relay described in connection with Fig. 3 may be used whenever circumstances 60 require.

A capacity device 31 is connected in series with the independent field winding 29^a and the inductance device 5 and, by proper adjustment, the inductive effect of the independent field and the resistance of the cir-

cuit, as well as the phase and amplitude of the voltage induced in the armature of the machine 28, may be adjusted to compensate for the effect of the leakage reactance and resistance of the induction machine 6.

Another modification of my proposed system is illustrated in Fig. 5 wherein anode leads 32 and 33 are shown as having inductive windings 34 and 35, respectively, in circuit therewith, and inductively inter-linked with a further inductive winding 36 which is connected in series with the independent field winding 29^a of the rotor 28. In this figure, as in Fig. 4, a capacity device 31 is also shown in the circuit.

Having described a number of systems constructed in accordance with my invention, the operation thereof is as follows:-

As above-mentioned, a number of loads, such as rectifiers, require high harmonic currents for their satisfactory operation and it is necessary, therefore, to provide such currents. At the same time, however, provision should be made to eliminate them from all portions of the electrical circuit except that part where they are specifically required.

Referring now to Fig. 1, if the machine 6 is run at the synchronous speed of the line frequency currents, it will offer a very high impedance to these currents and take only its own small magnetizing current of the line frequency. By supplying the machine with direct-current excitation, these currents can be even reduced to zero or reversed. On the other hand, the machine comprises practically a short circuit path for all other higher harmonic currents which it is desired to eliminate, and they will, therefore, be shunted out of the main supply circuit. The inductive devices 4 and 5, being placed 100 between the line and the eradicating means, assist in forcing the undesirable currents through the latter.

In Fig. 2 it is assumed that the load is supplied with energy from a line in which currents of differing frequencies are flowing, but that, for satisfactory operation, it must be supplied with currents of the fundamental frequency only. The eradicating means 6 is placed, therefore, between the source and the inductive devices 4 and 5, these latter serving to promote the flow of the undesirable currents through the winding 7.

Referring now to Fig. 3, it will be noted that the rectifier is shown as supplied with alternating current from the secondary of the transformer and is, in turn, supplying direct current to a load 1, in the well known manner. It, therefore, becomes necessary to eliminate the "ripple" currents from the load circuit 1, but, at the same time, to allow them to flow freely in the supply circuit of the rectifier.

In this connection, use is made of the machine 6 provided with the direct-current-excited winding 13, and connected across the secondary of the transformer. This system has the advantage that the leakage reactance of the transformer assists in keeping the higher harmonics out of the line which may render the use of inductances 4 and 5 unnecessary. Even if the inductance 10 4 is used, it may be made small.

Moreover, the use of a synchronous machine has the advantage that the power factor in the primary winding may be adjusted and that, thereby, it is possible to 15 shift whatever small irregularity in the wave shape which is not eliminated by the machine 6 to a point on the voltage curve where it is least objectionable in its effect.

The auxiliary commutator machine 28 is 20 run in such manner and excited in such direction that the voltage generated therein assists in causing the currents to flow in the desired circuit. A machine employed in this manner is known in the art as a negative 25 impedance.

The auxiliary apparatus, herein described as constituting the power-factor relay, is automatically operated by the current in the primary circuit of the transformer to adjust 30 the power factor in the desired manner and especially so that line frequency currents of the desired amplitude shall flow in the shunt circuit.

The system described in connection with 35 Fig. 4 operates in a similar manner to those above described with the exception that the current flowing in the independent field winding 29^a of the auxiliary machine 28 is varied by properly adjusting the capacity device 31. This latter method of adjusting the current in the independent field winding is productive of very satisfactory compensation of the leakage reactance and resistance of the main induction machine 6.

45 In Fig. 5 the current supplied to the independent field winding is varied in accordance with the load current of the rectifier, by reason of the inductive interlinkage of the three coils 34, 35 and 36. The auxiliary inductive winding 36 is so arranged that it carries the sum of the two currents flowing in the anode leads.

With the addition of the booster machine 28, the machine 6 might be replaced by a 55 highly saturated inductance, capacity, or even a high resistance, with the arrangements shown in Figs. 4 and 5. In some cases it is possible to use a commutator machine only, assuming, however, that its 60 excitation is properly adjusted. Before the rectifier is operative, the booster machine 28 may be used for starting service. In all cases, the induction motor is especially designed for low inductance and resistance.

65 While I have shown and described several

modifications of a system in which undesirable high-harmonic-absorption means are placed, it is apparent that many modifications in the manner of connection, specific apparatus used, etc. may occur to those skilled in the art, and I desire, therefore, that the widest possible interpretation be placed on the appended claims.

I claim as my invention:

1. An electrical system comprising alternating-current mains having translating devices connected thereto having negligibly small harmonic currents, second alternating-current mains having a translating device demanding abnormally large harmonic currents such as would harm the devices on said first-mentioned mains, connections between said first and second-mentioned mains and including series inductance, and a shunt-connected induction machine having a short-circuited secondary winding and having its primary winding connected to said second-mentioned mains.

2. In combination with an alternating-current circuit and a rectifier for interconnecting said circuit with a direct-current circuit, dynamo-electric means connected in parallel with said rectifier, and constituting a path of high impedance for currents having the frequency of said alternating-current circuit and low impedance for the undesirable-frequency currents occasioned by the operation of said rectifier, and a series inductance device between said alternating-current circuit and said rectifier.

3. In combination with an alternating-current circuit and a rectifier connected thereto, a squirrel-cage induction machine having its primary connected in parallel with said rectifier, and a series inductance device included in the connections between said rectifier and said alternating-current circuit.

4. In combination with an alternating-current circuit and a rectifier connected thereto, an induction machine having a primary winding connected in parallel with said rectifier, and having a low-impedance polyaxially short-circuited secondary winding and means whereby power-factor control may be obtained through said induction machine.

5. In combination with an alternating-current circuit, a rectifier and a transformer having primary and secondary members connected respectively to said circuit and said rectifier, dynamo-electric means energized from said transformer connected in parallel with said rectifier and constituting a path of relatively high impedance for currents having the frequency of said alternating-current circuit, and relatively low impedance for the undesirable-frequency currents occasioned by the operation of said rectifier.

6. In combination with an alternating-current circuit, a rectifier and a transformer having primary and secondary members connected respectively to said circuit and said rectifier, a dynamo-electric machine having primary, secondary and unidirectional-current windings, said primary winding being connected to said transformer in parallel with said rectifier, said secondary winding being polyaxially short-circuited, power-factor-control means comprising means for adjusting the excitation of said unidirectional-current winding, and means energized from said transformer primary for governing the adjustment of said power-factor-control means. 70
7. In combination with an alternating-current circuit, a rectifier and a transformer having primary and secondary members connected respectively to said circuit and said rectifier, an induction machine having its primary energized from said transformer in parallel with said rectifier and means for adjusting the phase of the higher harmonics relative to the phase of the primary fundamental wave of the transformer circuit. 85
8. In combination with an alternating-current circuit, a rectifier connected thereto, an induction machine having a primary connected in parallel with said rectifier, and means for adjusting the phase of the higher harmonics occasioned by the operation of said rectifier relative to the phase of the fundamental wave of the alternating-current circuit. 90
9. In combination with an alternating-current rectifier and a transformer supplying power thereto, dynamo-electric means for adjusting the phase of the higher-harmonic currents relative to the phase of the primary fundamental wave of the transformer current. 105
10. In combination with an alternating-current rectifier, means for absorbing higher-harmonic currents caused by the operation of said rectifier, and a commutator-type dynamo-electric machine having an armature and a field winding, said field winding being so energized and said armature being so connected, that the voltage developed in said armature shall promote the flow of said higher harmonics in said absorbing means. 110
11. In combination with an alternating-current rectifier, means for absorbing higher-harmonic currents caused by the operation of said rectifier, and a commutator-type dynamo-electric machine having an armature and a field winding, and a condenser in said field winding circuit serving to cause the voltage developed in said armature to promote the flow of said higher harmonics in said absorbing means. 115
12. In combination with an alternating-current rectifier supplied with energy from the secondary of a transformer, and having cathode and anode leads, inductive windings in each of said anode leads, means for absorbing higher-harmonic currents caused by the operation of said rectifier, and a commutator-type dynamo-electric machine having an armature and a field winding, an inductive winding in said field-winding circuit, said winding being inductively interlinked with said anode-lead windings, whereby said field winding is energized. 125
13. The combination with a circuit carrying currents of different frequencies, of a second circuit carrying currents of only one of said frequencies, dynamo-electric means connected in parallel across both of said circuits, said dynamo-electric means offering a relatively high impedance to currents of the frequency of said second circuit and a relatively low impedance to currents of the other frequencies, the connections between said dynamo-electric means and said first-mentioned circuit being of relatively low impedance, and the connections between said dynamo-electric means and said second circuit offering a relatively low impedance to currents of the frequency of said second circuit and a relatively high impedance to currents of the other frequencies. 130
14. The combination with a circuit carrying currents of a plurality of frequencies, of an electrical device connected thereto and adapted to carry currents of only one of said frequencies, selective-frequency means connected to said circuit for substantially eliminating currents of all other frequencies from said device, and means responsive to the currents of whatever frequencies flowing in said selective-frequency circuit to minimize the impedance of said last-mentioned circuit to said last-mentioned currents. 140
15. The combination with a circuit carrying currents of a plurality of frequencies, of an electrical device connected thereto and adapted to carry currents of only one of said frequencies, selective-frequency means connected in shunt with said device and offering a high impedance to currents of said frequency and a low impedance to currents of all other frequencies, and a booster in the shunt circuit for generating an assisting electromotive force responsive to the currents flowing therein. 150
16. The combination as specified in claim 15, including as the selective frequency means an induction machine adapted to offer a synchronous impedance to currents of the frequency obtaining in said device. 160
17. The combination as specified in claim 15, including as the booster a series, commutator-type alternating current machine. 165
18. In the combination of a circuit carrying currents of a plurality of frequencies, an electrical device connected thereto and

adapted to carry currents of only one of said frequencies, selective-frequency means connected in shunt with said device and offering a high impedance to currents of 5 said frequency and a low impedance to currents of all other frequencies, and a booster connected in series circuit relationship with said selective-frequency means and adapted to be responsive to currents 10 of all frequencies flowing in said means, the method of substantially precluding the flow of all but the desired frequency currents in said device, which consists in operating said booster under such conditions of 15 speed and excitation that the low impedance of said shunt circuit to currents of said other frequencies is substantially reduced.

19. In combination with an alternating current-rectifier, selective-impedance means 20 connected in shunt therewith for absorbing higher-harmonic currents caused by the operation of said rectifier, and means arranged to introduce into the absorbing circuit an electromotive force assisting the flow 25 of current therein.

20. In combination with an alternating-current rectifier, selective-impedance means for absorbing higher-harmonic currents caused by the operation of said rectifier, and an auxiliary dynamo-electric machine arranged to introduce into the absorbing circuit an electromotive force assisting the current-flow in said harmonic-absorbing means.

21. The combination with an alternating-current circuit including a device which would be harmed by abnormally large harmonic currents, of a double-wave rectifier device carrying such harmonic currents, selective-impedance means for offering a relatively low impedance to one or more of said harmonic currents, said means being connected in shunt relation to said rectifier device, and inductance means serially connected between said circuit and said rectifier device.

22. The combination with an alternating-current circuit including a device which would be harmed by abnormally large harmonic currents, of a rectified-current device carrying such harmonic currents, selective-impedance means associated with said device for providing a shunt path of relatively low impedance to one or more of said harmonic currents, and a series booster 25 device inserted in series with said selective-impedance means for augmenting the flow

of currents of whatever frequency flowing therein.

23. The combination with an alternating-current supply-line, of a transformer for deriving two secondary electromotive forces therefrom, means for providing a pair of oppositely disposed asymmetrically conducting paths respectively associated with said secondary electromotive forces, a direct-current circuit operatively associated with said paths, and selective-impedance means associated with the secondary electromotive forces of said transformer for providing a shunt path of relatively low impedance to one or 70 more of said harmonic currents, whereby said transformer operates, in effect, as an inductance device serially connected to said supply-line.

24. The combination with an alternating-current supply-line, of a transformer for deriving two secondary electromotive forces therefrom, means for providing a pair of oppositely disposed asymmetrically conducting paths respectively associated with said secondary electromotive forces, a direct-current circuit operatively associated with said paths, and a light running dynamo-electric machine having primary windings associated with said secondary electromotive forces and having a closely coupled, low-impedance secondary winding, whereby said transformer operates, in effect, as an inductance device serially connected to said supply-line.

25. The combination with an alternating-current supply-line, of a transformer for deriving two secondary electromotive forces therefrom, means for providing a pair of oppositely disposed asymmetrically conducting paths respectively associated with said secondary electromotive forces, a direct-current circuit operatively associated with said paths, a light running dynamo-electric machine having primary windings associated with said secondary electromotive forces and having a closely coupled, low-impedance secondary winding, and a negative impedance device inserted in series with said dynamo-electric machine for augmenting 105 the flow of currents of whatever frequency flowing therein.

In testimony whereof, I have hereunto subscribed my name this 4th day of December, 1918.

RUDOLF E. HELLMUND.
